UNITED STATES PATENT OFFICE

FRANK E. WILLIS, OF CHICAGO, ILLINOIS, ASSIGNOR OF ONE-HALF TO WALTER L. COHRS, OF CHICAGO, ILLINOIS

COMBINED COUNTER STIFFENER AND ARCH SUPPORT

Application filed February 4, 1928. Serial No. 251,810.

This invention relates to counter stiffening devices for shoes, and more particularly to a combined counter stiffener and arch support.

The device of my invention is intended to provide a counter stiffener and to effectively support the arch of the foot at both sides thereof in such manner as to strengthen and support the ligaments and tissues between the heel and the ball of the foot, as well as support the cuneiform bone. This device is formed of leather molded in rights and lefts and, due to its close contact with the foot is subject to the action of perspiration from the foot. In warm weather the effect of perspiration on a device of this character is particularly noticeable. It is the practice, in all devices of this character with which I am familiar, to dispose the flesh side of the leather at the inner face of the stiffener. This is objectionable as the flesh side of the leather used is fibrous and highly absorbent and the inner surface of the device soon becomes saturated with perspiration, in warm weather especially, which it retains. Upon removal of the shoe the stiffener dries and, as it dries, the inner portion thereof tends to shrink or draw together. This causes the upper portion of the stiffener to curl inwardly of the shoe, rendering it difficult to replace the shoe upon the foot. There is also the possibility of crushing the inwardly turned portion of the counter, under such condition, when inserting the foot into the shoe and permanently impairing the appearance of the shoe.

I have found that the above referred to inward curling of the upper edge portion of the counter stiffener is due to the fact that the flesh side of the leather is directed inwardly and, due to its absorbent nature, quickly becomes saturated with and retains perspiration from the foot. By properly constructing the stiffener this objection can be avoided. In accordance with my invention I form the stiffener of leather, as heretofore, but instead of having the flesh side of the leather at the inner face of the stiffener, as is the present practice, I dispose the flesh side at the outer surface of the stiffener and the hair or grain side of the leather at the

inner side of the stiffener. The grain side of the leather is relatively non-fibrous and non-absorbent and, therefore, the inner surface of the stiffener does not absorb and retain perspiration from the foot to an appreciable extent. As a result, when the stiffener dries after removal of the shoe from the foot, there is no tendency to curl inwardly of the upper portion of the device. In its broader aspect my invention consists in providing a counter stiffener having an inner portion or surface which is relatively non-absorbent and an outer portion or surface which is relatively highly absorbent. In the case of excessive perspiring of the foot, the perspiration will pass through the inner relatively non-absorbent surface of the stiffener and will be absorbed by the relatively highly absorbent outer surface thereof. Under such conditions, upon drying of the stiffener any tendency of the upper portion thereof to curl inwardly is counteracted by the tendency of the upper portion of the stiffener to curl outwardly due to the greater moisture content of the outer portion or surface of the stiffener and the natural tendency of this portion of the stiffener to shrink and turn outwardly at its upper edge portion as it dries. It will thus be seen that, by constructing the stiffener with a relatively non-absorbent inner surface and a relatively highly absorbent outer surface I prevent inward curling of the upper portion of the stiffener assuring that the appearance of the shoe is not impaired and facilitating replacing of the shoe upon the foot after removal thereof. Further objects and advantages will appear from the detail description.

In the drawings:

Fig. 1 is a perspective side view, partly broken away and in section of an Oxford shoe showing my invention applied thereto;

Fig. 2 is a transverse vertical sectional view through the heel portion of the shoe, the heel being shown in elevation, showing a counter stiffener constructed in accordance with my invention applied;

Fig. 3 is a fragmentary transverse sectional view through the heel portion of the

shoe, showing a counter stiffener of the present type as applied;

Fig. 4 is a perspective side view of a counter stiffener constructed in accordance with my invention;

Fig. 5 is a plan view of a blank from which my counter stiffener is formed.

My counter stiffener, designated in its entirety by 1, is shown as used in connection with a shoe of what is known as the Oxford type. The shoe includes an upper 2, an outer sole 3, a heel 4, and an inner lining 5, as well as an inner sole 6. The counter stiffener and arch support device 1 is formed of thick leather, preferably sole leather, and has its edge portion skived, the device thus formed having a thickened central portion. At its lower edge the stiffener 1 is provided with an inwardly turned portion or flange 6' which is sewed between the inner and the outer soles of the shoe, thus securing the stiffener in position. Also, as will be noted more clearly from Figs. 1 and 2, the stiffener is disposed between the upper 2 of the shoe and inner lining 5.

The stiffener 1 is of proper shape and size to extend from the first metatarsal bone of the large toe joint back around the heel and up to the fifth metatarsal bone at the little toe joint. It also extends forwardly beyond the cuboid bone on the outer side of the tarsus of the foot and the scaphoid bone of the inner side of the tarsus, being of a height to extend above such bone. This device grips the arch of the foot at opposite sides thereof in such manner as to effectively support the ligaments and the bones in the arch without gripping the foot too tightly. This serves to strengthen the arch by compacting the ligaments, tissues and bones thereof and keeps the weight of the body back of the toe joint or ball of the foot while allowing perfect freedom of motion of the joints in the fore part of the foot.

Devices of the general type above described are known in the art. It is the accepted practice, however, in constructing such devices to dispose the flesh side of the leather inwardly and the hair or grain side outwardly. As a result of this arrangement, after the shoe has been in use but a short time, the upper portion of the stiffener curls inwardly, as above noted, and with the disadvantages pointed out. This is particularly true in a device such as that illustrated and described which extends about the greater portion of the foot and in intimate contact therewith, though it is also true of leather counter stiffeners of usual type which are not extended along the sides of the foot. I have found that this inward curling of the upper portion of the counter stiffener can be avoided by disposing the grain side of the leather inwardly and the flesh side outwardly. In accordance with my invention the stiffener 1, which is shaped from a suitable blank, such as that illustrated

in Fig. 5, is formed of leather, the grain side 1^a of the leather forming the inner face of the stiffener and the flesh side 1^b forming the outer face thereof. For purposes of comparison, I have illustrated in Fig. 3 a stiffener 7 formed of leather in accordance with the present practice with the flesh side 7^a directed inwardly and the grain side 7^b disposed outwardly, this stiffener being shown as applied to a shoe of known construction. In use, the relatively highly porous inner face 7^a of the stiffener 7 absorbs and retains perspiration from the foot and when the shoe is removed the stiffener 7, upon drying thereof, tends to shrink or contract throughout its inner portion 7^a, this shrinking or drawing up of the inner relatively fibrous and absorbent inner portion 7^a of the stiffener causing the unsecured relatively thin upper edge portion 7^b to curl inwardly and downwardly as illustrated. By disposing the relatively non-fibrous and non-absorbent grain portion 1^a of the leather inwardly I avoid this absorption of the perspiration from the foot by the inner portion of the stiffener and, as a result, when the stiffener dries it does not curl downwardly and inwardly at the upper portion thereof as in the present form of stiffener. There is, therefore, from a practical standpoint a very decided advantage in constructing the stiffener of leather with the grain side thereof directed inwardly and the flesh side directed outwardly.

As stated, stiffeners constructed in accordance with my invention are molded in lefts and rights. This is advantageous, as the device is pre-formed to fit accurately the contour of the foot without binding or chafing and acts to best advantage to support the arch in the manner stated.

What I claim is:—

A counter stiffener for shoes comprising a piece of leather having a grain side and a flesh side and being formed to fit the foot of the wearer, and having the grain side disposed inwardly so as to face the foot of the wearer.

In witness whereof, I hereunto subscribe my name this 28th day of January, 1928.

FRANK E. WILLIS.
